Des. 187,159
Patented Feb. 2, 1960

187,159

IRON STAND

Maurice B. Vort, Great Neck, N.Y.

Application August 6, 1959, Serial No. 57,085

Term of patent 14 years

(Cl. D49—6)

Fig. 1 is a top plan view of an iron stand showing my new design.

Fig. 2 is an enlarged plan view of the iron stand.

Fig. 3 is a side elevation of the same.

Fig. 4 is a front elevation of the iron stand.

Fig. 5 is a rear elevation of the same.

I claim:

The ornamental design for an iron stand, substantially as shown.
